UNITED STATES PATENT OFFICE.

ROBERT A. FEROE, OF POTTSTOWN, PENNSYLVANIA.

BOX.

Application filed April 4, 1922. Serial No. 549,893.

To all whom it may concern:

Be it known that I, ROBERT A. FEROE, a citizen of the United States, and a resident of the city of Pottstown, county of Montgomery, and State of Pennsylvania, have invented certain new and useful Improvements in Boxes, of which the following is a specification, reference being had to the accompanying drawing.

10 My invention relates to boxes of cardboard or other suitable material intended for the reception of goods in a convenient and attractive manner and is more particularly applicable to boxes of the sort in which 15 men's socks are usually contained. These goods are ordinarily packed six or twelve pairs to the box, the socks being folded and banded together in such manner that the leg portions are superposed one on the other 20 adjacent one end of the rectangular and relatively narrow box while the feet are folded back on the legs from alternate sides, the result being that adjacent that end of the box opposite to that in which the upper 25 ends of the legs are disposed there is a small V-shaped or triangular opening with the apex substantially on the center line of the box which is not covered or filled by the goods. To facilitate the packing of the 30 socks in the box when folded in the manner described and to prevent them from moving about therein, it has been customary to secure adjacent each of the side walls of the box and so as to extend from what I 35 shall hereafter term the "upper" end for a suitable distance along the sides of the box, a cardboard filler thereby narrowing the available width of the box adjacent the narrow upper parts of the socks, and to also 40 secure adjacent the opposite or "lower" end of the box a triangular filler to occupy the space at that end which is not filled up by the folded socks.

Hitherto in the manufacture of such 45 boxes, the rectangular outer container or tray is first formed in the usual manner, a relatively narrow sheet of paper is then pasted along the inside of each side wall of the tray in such manner that it will project 50 thereabove so it can be folded down over the socks after the latter are placed in the box, and the three fillers formed of cardboard are then separately glued into position at the proper points adjacent the sides 55 and ends of the box, all of which requires time and a considerable number of different

operations with resultant expense. Additionally, the fillers are usually made of glazed cardboard and a good quality of paper used for the side flaps so as to present 60 an attractive finish, but the bottom of the tray is left uncovered so that when the socks are taken from the box, or if their position therein is disturbed in such manner that the bottom is exposed, the rough and unattractive looking stock of which the tray is 65 formed is exposed to view, thus detracting from the general appearance of the whole box.

A principal object of my invention is to 70 provide a box, and method of manufacturing the same, which is suitable for containing socks or the like when folded and packed in the customary manner but which may be manufactured at a greatly reduced cost over 75 the boxes hitherto in use for that purpose; which is more attractive in appearance than such boxes and in which the operations incident to gluing the side flaps and separate fillers in position are entirely avoided. A 80 further object of my invention is to provide a box for the purposes aforesaid in which the several fillers are formed from a single unitary blank and are integral therewith, the blank being cut and scored, preferably 85 in a single operation, in such manner that it may thereafter be readily folded to form the fillers and then deposited in the tray, preferably upon a single sheet of paper of sufficient width to fully line the tray, save 90 at the ends, and project above the side edges thereof for a suitable distance to form the side flaps, the inherent springiness or resiliency of the folded blank being sufficient 95 to cause its retention, as well as the retention of the paper, in the tray without the use of glue or other adhesive. Additionally, by making the blank of stock finished on the side which is exposed to view, the appearance of the box when empty or when 100 the position of the socks has been disturbed so as to expose portions of the bottom is materially enhanced over that of the usual boxes hitherto in use.

My invention further comprehends all of 105 the other objects and novel features of construction and arrangement hereinafter more particularly described or referred to or which appear from the accompanying drawings forming a part hereof.

In the said drawings I have illustrated 110 a preferred embodiment of my invention,

Fig. 1 being a perspective view of the box with the cover removed and portions of the side flaps broken away so as to more clearly show the interior arrangement; Fig. 2 is a composite perspective view showing the method of assembling the folded blank in the tray; Fig. 3 is a plan view of the blank before the same is folded, the points at which the blank is cut entirely through being indicated by full lines and those at which it is scored to facilitate the folding operation being indicated in dot and dash lines. Fig. 4 is a fragmentary top plan view of one end of the blank after folding with certain parts broken away; Fig. 5 is an inverted perspective view of the folded blank, and Fig. 6 a transverse section adjacent one end of the completed box. It will be understood that like numerals are used to indicate the same parts in the several figures and that it has been necessary to somewhat exaggerate the relative thickness of certain elements of the box, such as the paper side flaps. Additionally, for convenience of description I shall refer to that end of the box which is intended for the reception of the leg portions of the socks as the "upper" end and to the opposite end as the "lower" end and I have so designated them upon the drawing.

The completed box with the exception of the cover, which forms no part of the invention and is not shown, comprises three several elements, namely, the tray T, the paper lining P and the blank B, the tray and blank being ordinarily formed of cardboard or the like. The tray is rectangular in form comprising a bottom and side and end walls of a sufficient height to contain the articles to be packed in the box; is formed in the ordinary manner and is usually covered on its exterior or a portion thereof with suitable glazed paper. The lining P in the preferred embodiment of the invention is formed from a single rectangular sheet of paper of suitable finish, long enough to extend snugly between the ends E, E of the tray and wide enough to extend entirely across the bottom of the tray when disposed therein and upwardly along the sides S thereof to project above each side and form flaps F each of sufficient width when folded down over the goods to extend somewhat past the center line of the box and 55 slightly overlap the other flap.

The blank B is formed from a single piece of suitable stock preferably glazed or otherwise attractively finished on its upper side and is conveniently cut out and scored in the requisite manner, as hereinafter described, in a single operation. When so cut and scored the blank may be considered as comprising a plurality of separate yet integral elements relatively so disposed and 60 arranged as to form the three fillers when

the blank is folded up. The major portion of the blank consists of a base 1 symmetrical with respect to the longitudinally extending center line X—X and adapted when the blank is positioned in the tray to rest against the bottom thereof or against the surface of the paper P interposed between the blank and the bottom of the tray. The base is of generally relatively narrow elongated form with parallel side edges 2, 2' for a portion of its length and is terminated at its upper end by a transversely extending score 3, beyond which is disposed a rectangular upper end wall tab 4 of a size to fit against and substantially cover the upper end of the tray. In effect this tab is but a continuation of the body of the blank, the side edges of the tab lying in prolongations of the edges 2, 2', but the score 3 is only of a length equal to the desired distance between the upper fillers when the box is completed and beyond the ends of this score the blank is cut through as at 5, 5' so that the extreme lateral ends of the tab are unconnected with the base.

Adjacent its upper end the base is provided with laterally disposed extensions or wings symmetrically positioned on opposite sides of the line X—X and each of which is provided with certain scores and cuts in the following manner: A score 6 is extended parallel to X—X from each end of the score 3 toward the opposite end of the base for a distance equal to the desired length of the inner longitudinal wall of the upper filler, the transverse distance between these scores being equal to that desired between the fillers in the completed box, and a second similar score 7 is formed at a distance laterally outward from the score 6 equal to the desired height of the filler. At the lower ends of these scores the blank is cut transversely across at 8 for a distance substantially equal to the distance between the scores 6 and 7, thus defining a rectangular portion or region 9 which forms the inner side wall of the filler when the blank is bent up.

An additional score 10 is made in each wing parallel to the score 7 and at a distance therefrom equal to the desired width of the filler, and each wing is laterally terminated at an edge 11 parallel to the score 10 and at a distance therefrom substantially equal to that between the scores 6 and 7. The length of the score 10 and edge 11, however, beginning from lateral prolongation of the edges or cuts 5, 5' is somewhat greater than that of the scores 6 and 7, the region 12 included between the edge 11 and score 10 and which terminates at the transversely extending edge 13 being thus somewhat longer than the region 9. This region 12, which I term the outer side wall of the filler, is bounded at the end opposite the edge 13 by a trans-

versely extending score 14 which is in prolongation of the cuts or edges 5, 5', and an auxiliary end tab 15 preferably substantially square in shape is arranged on the 5 opposite side of score 14 and of the same width as the outer side wall. The region 17 between the scores 7 and 10 forms the top of the filler and is bounded at its lower end by a diagonal score 18 extending from 10 the end of the score 7 to the juncture of the edge 13 and score 10.

As hitherto stated, the blank is cut entirely through along the line 8 and also on a line 20 which extends from the inner end 15 of the cut 8 in an angularly outward direction parallel to the score 18, while the inner end of the edge 13 is connected with the outer end of the edge 20 by an edge 21 so that a region 22, which I term the inner side wall 20 tab, is formed and bounded by the score 18 and cuts or edges 8, 20 and 21.

It will be understood that the wings or extensions adjacent the upper end of the base are similar and symmetrical with respect to 25 the line X—X in all respects including the various cuts and scores, so that the foregoing description is equally applicable to both.

The lower end of the blank is also cut and 30 scored in a peculiar manner so that when folded up a triangular filler, which I term the lower filler, will be provided having its apex on the center line X—X and directed toward the upper end of the blank and its 35 base extending transversely across the blank in a position to contact with the lower end of the tray. In order to accomplish these results the lower end of the blank is cut and scored in a manner which is non-symmetrical 40 with respect to the line X—X and which will now be described.

A transversely extending score 30 is provided of a length equal to the width of the inside of the tray and a rectangular tab 31 45 designed to form the lower end wall of the blank and of a size substantially equal to the end of the tray is defined on one side by this score and on its other three sides by edges 33, 34 extending parallel to the line X—X and a transversely extending edge 35 connecting them. The length of the edge 2 is such that the distance between the cut or edge 5 and the termination of the edge 2 adjacent the lower end of the blank is 55 substantially equal to the inside length of the tray T, and a diagonal and inwardly extending edge 37 is arranged to connect the lower end of the edge 2 with the inner end of the edge 33, the angle between the edge 37 and the edge 2 in the preferred form of the invention being substantially 150° and the length of this edge 37 being substantially 60 equal to the width of the tab 31 measured along the line X—X, or in other words, to 65 the depth of the tray.

Extending diagonally inwardly toward line X—X from each end of the edge 37 are scores 38 and 39 which are parallel to each other, the score 38 terminating substantially on the line X—X and being connected from such termination with the score 39 by a score 40 parallel to the edge 37. Thus a rectangular region 41 is defined, which forms one of the diagonally disposed vertical walls of the lower filler when the blank is folded up. 70

Extending inwardly toward the line X—X from the juncture of the score 30 and edge 34 is a score 43, the angle between this score and the score 30 being the same as that between the latter and the score 39, so that a region 45 forming the lower filler top and in the form of an isosceles triangle is defined by the scores 30, 39 and 43, the apex of this region being, however, laterally offset or spaced from the line X—X. From the juncture of the scores 30, 43 and edge 34, an edge 47 is extended angularly outward substantially normal to the score 43 and a cut 48 is extended parallel thereto from the juncture of the scores 39 and 43, a score 49 extending parallel to score 43 being arranged to connect the extremities of these edges, thus defining a region 50 which forms the other vertical angularly disposed face of the lower filler when the blank is folded. A tab 52, which I term the sub-base tab, and which is preferably substantially in the form of an equilateral triangle, is arranged to extend outwardly from the score 49 which forms one of its sides, the edges 53 and 54 forming the others, the former being substantially parallel to the line X—X. 90

There is also provided in the blank a cut 56 extending substantially from the juncture of the scores 38 and 40 to the cut 48 and normal to the latter, so that a substantially right triangular tab 60 is formed and attached only to the region 41 along the score 40; this tab forms the lower filler lock tab 100 when the blank is folded.

Preferably also I terminate the lower end of the edge 2' a short distance from the edge 54 and connect the extremity of the edge 2' with the edge 48 by an edge 48' which may be either straight or slightly curved as shown and is in effect a substantial prolongation of the edge 48. 110

It will be understood that in the foregoing description of the blank I have employed the terms "cut" or "edge" interchangeably since frequently what is in the flat blank only a cut or slit with the adjacent edges in contact or substantially contact, entirely disappears when the blank is folded on account of the edges being separated or extended in different directions. 120

The blank cut and scored in the manner hitherto described is folded so that the portions 9 will extend from the scores 6 at right 130

angles to the base, the portions 17 in a direction parallel to the base and the portions 12 vertically downward therefrom, the edges of the tabs 22 adjacent the portions 9 being tucked behind them with the tab extending vertically down from the score 18. The upper end wall tab 4 is then bent vertically up from the score 18 and the auxiliary end tabs 15 folded at right angles to the portion 12 and brought around behind the wall tab 4, the parts just described thus assuming the positions shown in Fig. 2. The various parts adjacent the lower end of the blank are also folded in such manner that the lower end wall 31 and portions 41 and 50 extend vertically up from the base, the small triangular lock tab 60 being tucked behind the wall 50 and the sub-base tab 52 being bent along the score 49 at right angles to the portion 50 and partially entered beneath the base, also as best shown in Fig. 2. The blank is now in condition to be disposed upon the paper P which has previously been positioned in the tray, and it will be found that when so disposed the resiliency or springiness of the several parts of the blank is sufficient to hold the latter in position in the tray with sufficient rigidity for practical purposes, as the tray may be turned upside down or shaken without the blank falling out.

It will be observed that the construction of the blank is such that the folding and creasing thereof becomes a relatively simple matter and that there are no small tabs or projections which are required to be inserted in slits or slots and then bent over in order to hold the parts in proper position. Moreover, by reason of the peculiar arrangement of the cuts and scores adjacent the lower end of the blank, when the parts are properly folded the apex of the triangular top of the lower filler becomes substantially coincident with the vertical plane passing through the line X—X, so that the lower filler is symmetrically disposed with respect to the blank and in turn to the completed box.

It will be understood that while I have described and illustrated herein a preferred embodiment of my invention with considerable particularity, I do not thereby desire or intend to specifically limit myself thereto as suitable changes and modifications may be made therein as desired without departing from the spirit and scope of the invention, as defined in the appended claims.

Having thus described my invention, I claim and desire to protect by Letters Patent of the United States:

1. A blank adapted to be positioned in a rectangular tray and having a part arranged to form a base and portions adjacent one end thereof so cut and scored that when bent to a predetermined position prior to insertion

in the tray a filler will be formed at one end of the base triangular in planary outline and having walls extending substantially normal to the base, said blank for the purpose of forming said filler being provided with scores disposed to define an isosceles triangle with its altitude parallel to the center line of the base but laterally spaced therefrom, similar rectangular portions extending from the sides of the triangle and each defined by cut and scored lines, and a tab in the form of an equilateral triangle extending from one of the longer sides of one of said rectangular portions and adapted when the blank is bent to final position to partially enter beneath the base.

2. A blank adapted to be positioned in a rectangular tray and having a part arranged to form a base and portions adjacent one end thereof so cut and scored that when bent to a predetermined position prior to insertion in the tray a filler will be formed at one end of the base triangular in planary outline and having walls extending substantially normal to the base, said blank for the purpose of forming said filler being provided with scores disposed to define an isosceles triangle with its altitude parallel to the center line of the base but laterally spaced therefrom, similar rectangular portions extending from the sides of the triangle and each defined by cut and scored lines, a tab in the form of an equilateral triangle extending from one of the longer sides of one of said rectangular portions and adapted when the blank is bent to final position to partially enter beneath the base, and a substantially triangular tab extending from one of the shorter sides of the other of said portions.

3. A blank adapted to be positioned in a rectangular tray and having a portion arranged to form a base and portions adjacent one end thereof so cut and scored that when bent to a predetermined position a filler will be formed at one end of the base, said filler being triangular in planary outline and having vertical walls; said blank for the purpose of forming said filler having scores disposed to define an isosceles triangle with its altitude parallel to the center line of the base but laterally spaced therefrom, similar rectangular portions extending from the sides of the triangle and defined by cut and scored lines, a corner of one said portions being coincident with the center line of the blank, a tab in the form of an equilateral triangle extending from one of the longer sides of the other said portions and adapted when the blank is bent to final position to partially enter beneath the base, and a rectangular tab extending from the base of the triangle.

In witness whereof, I have hereunto set my hand this 31 day of March, 1922.

ROBERT A. FEROE.
